UNITED STATES PATENT OFFICE.

FRANK W. SCHWINN, OF CHICAGO, ILLINOIS.

MOTOR-CYCLE STAND.

Application filed June 22, 1921. Serial No. 479,510.

To all whom it may concern:

Be it known that I, FRANK W. SCHWINN, a citizen of the United States, residing at 3700 Cortland Street, Chicago, in the 5 county of Cook and State of Illinois, have invented a new and useful Improvement in Motor-Cycle Stands, of which the following is a specification.

This invention relates to motor cycle stands and the like and is fully described in the following specification and shown in the accompanying drawings, in which:

Figure 1 is a diagrammatic side elevation of a motor cycle mounted in operative position thereon;

Fig. 2 is an enlarged partial section on the line 2 of Fig. 1 showing the stand in operative position;

Fig. 3 is a similar view showing the stand 20 in inoperative position;

Fig. 4 is an enlarged detail of the connection of the foot when in operative position;

Fig. 5 is a similar view of the connection 25 with the foot in inoperative position;

Fig. 6 is a partial plan view of the support for the foot; and

Fig. 7 is an enlarged partial section on the line 7 showing the ground engaging end 30 of the support.

In the embodiment illustrated the motor cycle frame has a side bar 10 extending along the side of the rear wheel 11. The lug 12 is secured to the frame member 10 35 as by means of a bolt 13. This lug extends to the side of the motor cycle and has a bifurcated ear 14 through which extends a bolt 15.

A foot 16 has a narrow end 17 which fits 40 between the bifurcated ears 14 and has an elongated slot 18 which extends parallel to the sides of the foot.

An inclined wall 19 is formed between the bifurcated ears 14 and at a distance from the 45 center of the bolt 15 equal to half the width of the end 17. The end 17 of the foot is rounded and the slot 18 extends near enough to this end to permit the foot 16 to be freely swung about the bolt 15 through an arc of 50 180°, so long as the bolt 15 is maintained at the outer end of the slot 18.

It will be clear, however, that as the foot 55 16 is swung so as to be parallel to the wall 19 and moves endwise so as to place the bolt 15 at the inner end of the slot 18, the

foot will be locked against rotary movement about the bolt 15. This may be true in either the down or up positions of the foot as shown in Figs. 4 and 5 respectively. With the foot 16 in the down position as 60 shown in Figs. 2 and 4 the weight of the motor cycle will partly rest upon the foot 16 and consequently a side pressure on this foot will not cause it to swing up and thus permit the motor cycle to topple over. 65

With the foot in inoperative position as shown in Fig. 3 it is necessary to provide some locking means, otherwise a sudden jolt might cause the foot 16 to jump up and to swing down and into the operative position at which time there would be great danger that it would strike the road way and cause the rider to be thrown. In order to prevent this I have provided a depression 20 inside of the foot 16 and a plunger 70 21 engageable therewith and forced outwardly by means of the spring 22.

It will thus be seen that with the foot in the position shown in Fig. 5, the plunger 21 will fall into the depression 20 and will 80 hold the foot in this position. A considerable jerk is required to unlock the foot so that accidental release is precluded. In order to lock this member it is first turned to the up position and a blow of the hand 85 drops it down into locked position.

In Fig. 7 is shown the ground gripping foot which consists of a series of sharp concentric corrugations 23.

While I have shown and described but a 90 single embodiment of my invention, it is to be understood that it is capable of many modifications. Changes, therefore, in the construction and arrangement may be made without departing from the spirit and scope 95 of the invention as disclosed in the appended claims, in which it is my intention to claim all novelty inherent in my invention as broadly as possible in view of the prior art.

What I claim as new and desire to secure 100 by Letters Patent is:

1. A stand for motor cycles and the like comprising a member adapted to be secured to the frame of the motor cycle, a foot hingedly mounted on said member and 105 adapted to swing up to an inoperative position and to swing down so as to reach the ground in an operative position, a longitudinal slot in said foot having parallel sides, a pin on said member passing 110

through said slot and a wall on said member adjacent said pin, and at a distance therefrom equal to half the thickness of said foot at the slotted end whereby the weight of the 5 frame in the operative position holds the foot locked against said wall.

2. A stand for motor cycles and the like comprising a member adapted to be secured to the frame of the motor cycle, a foot 10 hingedly mounted on said member adapted to swing to an inoperative position and to swing down so as to reach the ground in an operative position, a longitudinal slot in said foot, a pin on said member passing 15 through said slot, a wall on said member adjacent said pin and at a distance therefrom equal to half the thickness of said foot at the slotted end, a depression in the side of said foot at the slotted end and a 20 spring pressed plunger adapted to engage said depression when the foot is raised to the inoperative position and the pin is at

the inner end of said slot, to hold the foot in said position.

3. A stand for motor cycles and the like 25 comprising a member adapted to be secured to the frame of the motor cycle, a foot hingedly mounted on said member and adapted to swing up to an inoperative position and to swing down so as to reach the 30 ground in an operative position, a longitudinal slot in said foot, a pin on said member passing through said slot, a wall on said member adjacent said pin, and at a distance therefrom equal to half the thickness 35 of said foot at the slotted end, whereby the foot is held by said wall in both operative and inoperative positions when the pin is at the inner end of the slot, and means operable by the longitudinal movement of said 40 foot for holding it in either of said positions.

FRANK W. SCHWINN.
